ATTORNEYS.

UNITED STATES PATENT OFFICE.

JAMES B. McDEVITT AND MARIUS GREENSPAN, OF CHICAGO, ILLINOIS.

DESIGN FOR AN AUTOMOBILE-TIRE.

52,062.

Specification for Design.

Patented May 28, 1918.

Application filed April 17, 1917. Serial No. 162,775. Term of patent 14 years.

To all whom it may concern:

Be it known that we, JAMES B. McDEVITT and MARIUS GREENSPAN, citizens of the United States, residing at Chicago, in the county of Cook and State of Illinois, have invented a new, original, and ornamental Design for Automobile-Tires, of which the following is a specification, reference being had to the accompanying drawing, in which—

We claim:—

The ornamental design for an automobile tire, as shown.

In testimony whereof we affix our signatures, in the presence of a witness.

JAMES B. McDEVITT.
MARIUS GREENSPAN.

Witness:

S. J. LEHRER.
